CLAIM

The ornamental design for a cup with integrated folding lid
as shown and described.

DESCRIPTION

FIG. 1 is a perspective view of a cup with integrated folding lid showing our new design, in an unfolded configuration;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a front perspective view thereof in a partially-folded configuration;
FIG. 9 is a front perspective view thereof in a further partially-folded configuration;
FIG. 10 is a front perspective view thereof in a fully-folded configuration; and,
FIG. 11 is a front perspective view thereof in a fully-folded configuration, shown with an exemplary straw in a position of use.

The broken lines shown are for the purpose of illustrating environmental subject matter of an exemplary straw that forms no part of the claimed design and for illustrating portions of the cup with integrated folding lid that form no part of the claimed design.
